[57] CLAIM

The ornamental design for a holder for rod shaped articles, as shown and described.

DESCRIPTION

FIG. 1 is a top view of a holder for rod shaped articles showing my new design;

FIG. 2 is a front view thereof;

FIG. 3 is a bottom view thereof;

FIG. 4 is an end view taken from the left of FIG. 2;

FIG. 5 is an end view taken from the right of FIG. 2;

FIG. 6 is a front view thereof showing the movable parts in different positions;

FIG. 7 is a top view of a second embodiment of the design of FIG. 1;

FIG. 8 is a front view of FIG. 7;

FIG. 9 is a bottom view of FIG. 7;

FIG. 10 is an end view taken from the right of FIG. 7;

FIG. 11 is an end view taken from the left of FIG. 7.

The back of the holder in both embodiments is plain.
